UNITED STATES PATENT OFFICE.

KARL LENDRICH, OF HAMBURG, GERMANY, ASSIGNOR TO HUGO LIEBER, OF NEW YORK, N. Y.

LIQUID SOAP AND PROCESS OF PRODUCING THE SAME.

No. 895,477.

Specification of Letters Patent.

Patented Aug. 11, 1908.

Application filed April 5, 1907. Serial No. 366,494.

To all whom it may concern:

Be it known that I, KARL LENDRICH, a subject of the Empire of Germany, residing in Hamburg, Germany, have invented certain new and useful Improvements in Liquid Soap and Processes of Producing the Same, of which the following is a specification.

This invention relates to a soap or composition which is soluble in and in which ether, 10 lignoine, benzin, petroleum ether, gasolene, petroleum, benzol, toluol, xylol, chloroform, oil of turpentine, carbon bisulfid, carbon tetrachlorid and organic compounds like these fluids are readily soluble in any proportion, 15 and to the process of producing such soap or composition, and has for its object the many useful purposes for which such soap or composition is adapted and the many advantages thereof.

Most of the above mentioned organic compounds are of highly explosive nature; they also evaporate readily and possess great inflammability. It is, moreover, exceedingly difficult to mix these organic compounds 20 with other materials or to produce an emulsion thereof which will reduce the danger of explosion and of inflammability and prevent their quick evaporation. For the reasons stated and for other well known reasons, it 25 has heretofore been almost impossible to use the above mentioned materials or organic compounds for purposes for which they could have been used with great advantage if the difficulties mentioned and referred to could 30 have been overcome. By the aid of the liquid soap or composition, which is the subject of this invention, a mixture of the soap or composition with the above mentioned materials or organic compounds can be produced 35 and this mixture can readily be emulsified in any proportion with a suitable substance or liquid, such as, especially, water.

The production of the solvent and soluble liquid soap according to this invention is 40 based upon the observation that the potassium compounds of the unsaturated fatty acids, and of these especially those of the linolie acid and linolenic acid, have, under certain conditions, the property of being soluble 45 in the above mentioned organic fluids. The conditions necessary for this purpose exist in the kind and quality of the raw materials used for the production of these compounds and in the method itself of production.

Raw materials to be considered are:—

(1). Vegetable or animal oils, which are especially rich in compounds of the unsaturated, fatty acids and particularly in linolie acid and linolenic acid, or the free, fatty acids eliminated out of such oils.

(2). A potash lye of a certain concentration and purity.

(3). Spirits such as alcohol or methyl alcohol of a certain strength. 65

From practical experience and extensive experiments, I have found that the following raw materials are especially to be considered in the production of the liquid soap;—

(1). Refined corn oil or refined linseed oil. 70

(2). Watery potash lye containing preferably fifty per cent. potassium hydroxid, which must be free from sodium hydroxid and as free as possible from carbonates and chlorids. Especially suitable is the fifty per 75 cent. commercial potash lye made by the electrolytic process.

(3). Denatured spirits containing, preferably, not less than ninety-four per cent. in weight of alcohol, which may be denatured with benzin; methyl alcohol containing, preferably, not over ten per cent. acetone. Spirits are preferable to methyl alcohol, since with the former the process is quicker and smoother. 85

By the use of the foregoing substances, the production of the liquid soap, without any use of artificial heat, is as follows;—100 parts by weight of corn oil or linseed oil and 62 parts by weight of denatured spirits with 90 not less than 94% by weight of alcohol are thoroughly mixed in a suitable, tightly-closed vessel, corresponding in size to the quantity of soap to be made, until an even emulsion is formed. A rotary drum or a 95 stationary vessel with a mixing apparatus is well adapted for this purpose. Thereupon, 37 parts by weight of a 50% watery, potash lye are added and the mixture is again thoroughly mixed for a short time until a drawn 100 sample shows a perfectly clear solution. The solution becomes clear after a very few minutes under heat generation. After this the soap is drawn off into vessels and should be kept standing for twenty-four hours longer 105 in order to bring on a perfect saponification. After this the soap is ready for use.

Any material departure from these instructions is not advantageous to the soap and may impair its qualities and properties 110

with respect to the solubility therein of the above mentioned organic fluids and with respect to its solubility in said fluids; although, as will be well understood, variations may be 5 employed without departing from the principle of my invention.

The soap manufactured according to the above described process is almost neutral; at a temperature of over fifteen degrees Celsius 10 is a thin fluid (becoming slightly like gelatin at a lower temperature, which can be quickly overcome through warming); and possesses the property of dissolving clear, in any proportion, the above mentioned organic fluids. 15 These solutions of the organic compounds in the soap possess, furthermore, the property of producing, through mixture with water, exceedingly fine and durable emulsions.

In order to produce especially durable and 20 effective emulsions, not less than ten per cent. of the fluid soap should be contained in the organic fluids to be emulsified.

The employment of the above mentioned organic fluids in the form of emulsions has 25 many advantages over their direct employment, and the means of such emulsions, the fluid soap, has no deteriorating effects. The emulsion permits the organic fluids to be used in any strength of solution and the effects 30 thereof, when in emulsions, are much greater than those which the substances would have when used directly. The usually quick evaporation of the said organic fluids is considerably prolonged when in the form of 35 emulsions and is then not greater than that of water; by reason whereof the effects become much greater than those of the fluids themselves. The penetrating power of the emulsions is also considerably greater than 40 that of the organic fluids used directly, especially when used as germ destroyers for microbes on plants in the culture of forests, lands, and gardens.

Since the above mentioned organic fluids 45 are either lighter or heavier than water, it is recommended to make the emulsions, especially when made in large quantities, in the following manner;—Two parts by weight of the organic fluid to be emulsified, mixed with 50 two-tenths part of the fluid soap, are thoroughly mixed with one part by weight of water, whereby a thick fluid emulsion is obtained, which is then poured in a thin stream into water, which is under constant stirring, 55 until the desired dilution is obtained.

The emulsions of the above mentioned organic fluids or compounds made by means of the fluid soap, in accordance with this invention, are useful for many divers purposes. 60 They may, for example, be employed for cleansing purposes and they are especially valuable, for the reasons above stated, for use as germ destroyers, being applied in the form of a spray or other suitable manner to 65 trees, plants and other germ carrying objects.

What I claim is;

1. A liquid soap, in which benzin is readily soluble, consisting of ingredients resulting from a mixture of suitable oil, spirits and potash lye, substantially as described. 70

2. A liquid soap, in which benzin is readily soluble, consisting of ingredients resulting from a mixture, approximately, of 100 parts by weight of suitable oil, 62 parts by weight of spirits, and 37 parts by weight 75 of potash lye, substantially as described.

3. A liquid soap, in which benzin is readily soluble, consisting of ingredients resulting from a mixture of suitable vegetable oil, alcohol and potash lye, substantially 80 free from sodium hydroxid and from carbonates and chlorids, substantially as described.

4. A liquid soap, in which benzin is readily soluble, consisting of ingredients resulting from a mixture of oil, rich in compounds of the unsaturated, fatty acids, 85 spirits and potash lye, substantially free from sodium hydroxid and from carbonates and chlorids, substantially as described.

5. A liquid soap, in which benzin is 90 readily soluble, consisting of ingredients resulting from a mixture of suitable oil, rich in compounds of the unsaturated, fatty acids, spirits and potash lye, containing fifty percent. potassium hydroxid substantially free 95 from sodium hydroxid and from carbonates and chlorids, substantially as described.

6. A liquid soap, readily soluble in benzin, consisting of ingredients resulting from a mixture of suitable oil, spirits and potash 100 lye, substantially as described.

7. A liquid soap, readily soluble in benzin, consisting of ingredients resulting from a mixture, approximately, of 100 parts by weight of suitable oil, 62 parts by weight of 105 spirits, and 37 parts by weight of potash lye, substantially as described.

8. A liquid soap in which benzin is readily soluble having an organic compound such as benzin dissolved in it and consisting 110 of ingredients resulting from a mixture of suitable oil, spirits and potash lye, substantially as described.

9. A liquid soap in which benzin is readily soluble having an organic compound 115 such as benzin dissolved in it and consisting of ingredients resulting from a mixture, approximately, of 100 parts by weight of suitable oil, 62 parts by weight of spirits, and 37 parts by weight of potash lye, substantially 120 as described.

10. A liquid soap readily soluble in benzin, dissolved in an organic compound such as benzin and consisting of ingredients resulting from a mixture of suitable oil, spirits 125 and potash lye, substantially as described.

11. A liquid soap readily soluble in benzin, dissolved in an organic compound such as benzin and consisting of ingredients resulting from a mixture, approximately, of 130

100 parts by weight of suitable oil, 62 parts by weight of spirits, and 37 parts by weight of potash lye, substantially as described.

12. The process of making a liquid soap in which benzin is readily soluble, consisting in mixing, approximately, 100 parts by weight of a suitable oil with 62 parts by weight of spirits and adding to the mixture 37 parts by weight of potash lye, substantially as described.

10 scribed.

13. The process of making a liquid soap in which benzin is readily soluble, consisting in mixing, approximately and without the use of artificial heat, 100 parts by weight of a suitable oil with 62 parts by weight of spirits and adding to the mixture 37 parts by weight of potash lye, substantially as described.

14. The process of dissolving an organic compound such as benzin in a liquid soap, consisting in making a liquid soap in which benzin is readily soluble, by mixing, approximately, 100 parts by weight of a suitable oil with 62 parts by weight of spirits and adding to the mixture 37 parts by weight of potash lye and then mixing the organic compound with the liquid soap, substantially as described.

15. The process of producing, by means of a liquid soap, an emulsion of an organic com-

1 pound such as benzin, consisting in making 30 a liquid soap in which benzin is readily soluble, by mixing, approximately, 100 parts by weight of a suitable oil with 62 parts by weight of spirits and adding to the mixture 37 parts by weight of potash lye, then mixing 35 the organic compound with the liquid soap and then adding to said mixture and mixing therewith water, substantially as described.

16. A liquid soap readily soluble in benzin, consisting of ingredients resulting from 40 a mixture of suitable oil, spirits and potash lye, dissolved in an organic compound, such as benzin, and mixed with water, substantially as described.

17. A liquid soap in which benzin is 45 readily soluble, consisting of ingredients resulting from a mixture of suitable oil, spirits and potash lye, having dissolved in it an organic compound, such as benzin, and mixed with water, substantially as described. 50

In witness whereof, I have set my hand to this specification in the presence of two subscribing witnesses, this sixth day of March 1907.

KARL LENDRICH.
